UNITED STATES PATENT OFFICE.

MILDRED C. SCHMOLZE, OF NEW YORK, N. Y., ASSIGNOR TO FRANKLIN SIMON & CO.,
OF NEW YORK, N. Y., A CORPORATION OF NEW YORK.

DESIGN FOR A DRESS.

Application filed January 5, 1925. Serial No. 11,930. Term of patent 3½ years.

To all whom it may concern:

Be it known that I, MILDRED C. SCHMOLZE, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the skirt is distinguished by having spaced box plaits with accordion plaits therebetween and the blouse distinguished by vertical plaits on each side and a

pair of parallel lines of pin tucks with a belt formed with pin tucks and an ornamental handkerchief partly projecting from the belt of the same color as the ornamental tie arranged immediately below the neck opening, the handkerchief and tie being of contrasting color to the blouse and skirt.

The figure is a front view of a dress, showing my new design.

I claim:

The ornamental design for a dress, substantially as shown and described.

MILDRED C. SCHMOLZE.
